UNITED STATES PATENT OFFICE.

WILLIAM S. LENHART, OF ATLANTIC CITY, NEW JERSEY.

CARBURETER.

1,271,181.

Specification of Letters Patent.

Patented July 2, 1918.

Application filed June 17, 1916. Serial No. 104,226.

To all whom it may concern:

Be it known that I, WILLIAM S. LENHART, a citizen of the United States, residing at Atlantic City, county of Atlantic, and State of New Jersey, have invented new and useful Improvements in Carbureters, of which the following is a specification.

My invention relates to new and useful improvements in carbureters, and has for its object to provide a device of this character for use with internal combustion engines where the products of combustion will be utilized to heat the air which is conveyed to the carbureting chamber and passed through the gasoline or other volatile liquid to form a highly explosive mixture for use in the engine, said mixture when leaving the carbureting chamber being in a dry state.

A further object of the invention is to provide a carbureting chamber surrounding a central standpipe, the latter having communication with the air and gasoline inlets, so that they may be mixed in the standpipe as well as in the carbureting chamber, thereby providing two compartments in which the carbureting action may take place, so that either a dry or moist mixture may be produced.

A still further object of the invention is to provide a casing having a duct leading from the inlet to an annular passageway from which lead numerous small passageways or ducts to the carbureting chamber at the lower end thereof, so that the air is delivered to the carbureting chamber at the lower end thereof, and caused to pass through the volatile liquid where the air will mix with said liquid and produce a relatively dry mixture, so that its use in an engine will eliminate or greatly reduce the formation of carbon on the inner walls of the engine cylinders.

Another object of the invention is to provide means for priming without passing the air through the volatile liquid preliminary to starting an engine.

Another object of the invention is to provide means for producing a partial vacuum in the gasoline reservoir or float chamber, so that the gasoline may be maintained at a predetermined level in the float chamber regardless of the position of the gasoline supply tank.

With these ends in view, my invention consists in the details of construction and combination of elements hereinafter set

forth and then especially designated by the claims.

In order that those skilled in the art to which this invention appertains, may understand how to make and use the same, I will describe its construction in detail, referring by numerals to the accompanying drawings forming a part of this application, in which—

Fig. 1, is a vertical sectional view of my improved carbureter.

Fig. 2, is a section at the line 2—2 of Fig. 1.

Fig. 3, is a section at the line 3—3 of Fig. 1.

Fig. 4, is a bottom view of a carbureter showing portions thereof in section to clearly illustrate the constructions.

Fig. 5, is a segmental sectional view on the line 5—5 of Fig. 4; and

Fig. 6, is a segmental sectional view of the standpipe illustrating the construction of the priming, duct and the spray nozzle.

In carrying out my invention as here embodied 2 represents the exhaust pipe of an explosive engine surrounded by a shield or jacket 3 provided with an inlet as at 3' having an outlet 4 which communicates with a pipe 5, the latter communicating with the inlet opening 6 of the carbureter casing 7 and provided with air inlet openings 8 adjacent the inlet of the carbureter, said openings being controlled by a damper 9 in the form of a slotted annular band operated in any suitable manner as by an operating handle 10. The outer end of the inlet 6 of the carbureter casing is enlarged to form a shoulder 11, against which rests a foraminous member 12 such as wire gauze, the same being held in place by the end of the pipe 5 which is threaded into the enlarged portion of the inlet 6. From the inlet 6 leads a vertical duct 13 to an annular passageway 14 at the upper end of the casing, said passageway 14 passing entirely around the casing and communicating with numerous small vertical passageways or ducts 15 disposed around the carbureting chamber 16 and communicating therewith at its lower end through holes 17, some of which are slightly higher than the rest as at 18 to permit the formation of a gasoline inlet 19, also leading to the lower end of the carbureting chamber.

Within the carbureting chamber and central thereof is situated the standpipe 20 com-

municating with a horizontal duct or air inlet pipe 21 which terminates adjacent the end of the inlet 6 of the carbureter and communicates with said inlet. This passageway is controlled by the throttle or butterfly valve 22, operated in any suitable manner as by a handle 23. This inlet or passageway is also provided with a drip cock 24.

The upper end of the standpipe 20 terminates on line with the upper end of the carbureter casing 7, and on the latter is mounted a cap or cover 25 secured to the casing in any suitable manner as by bolts 26, and having formed therewith the central depending cup shaped member 27 open at the top and bottom and provided with inlet slots or openings 28, and the lower end of this cup shaped member engages the upper end of the standpipe 20 when the cap or cover is in position upon the casing, and if found desirable, a gasket 29 may be placed between the contacting parts.

This cap or cover is also provided with a conduit 30, one end of which communicates with the interior of the cup shaped member 27, the other end terminating at the lower face of the cap or cover 25 beyond the edge thereof.

Within the cup shaped member 27 is rotatably mounted the valve member or damper 31 having slots 32 adapted to align with the slots 28 and provided with a cutout portion or notch 33 to prevent the closing of the conduit 30 when said member is rotated, and in order that said member may be rotated I provide means 34, such as an operating handle, which is secured to the valve member or damper 31, and passes through a slot 35 in the cup shaped portion of the cover 25.

To the cover 25 is attached the outlet pipe 36 having an opening 37 in communication with the cup shaped member of the cover, said opening being surrounded by a valve seat 38 with which coacts a valve 39 having a stem 40 passing through a bridge 41 across the opening 37, and having a spring 42 coiled thereabout, one end resting against the underside of the bridge as the stationary member, and the other end against a nut 43 or its equivalent mounted on the end of the stem 40. This valve operates inward with relation to the outlet, so that the mixture may be drawn into said outlet from the carbureting chamber by the suction of the engine.

The outlet pipe 36 is further provided with an opening 44 in its side wall, and a valve seat 45 is formed thereabout with which coacts a valve 46 having a stem 47 passing through the bridge 48 disposed across the opening 44 and having a spring 49 coiled thereabout and resting against the bridge 48, and a nut or its equivalent mounted on the end of the stem for normally holding the valve closed. This valve operates outward, so that should the engine back fire

or explode prematurely, the pressure produced thereby within the outlet pipe 36 will be relieved.

The passageway through the outlet 36 is controlled by a throttle or butterfly valve 51 mounted in said outlet pipe beyond the valve 46, and actuated in any suitable manner as by an operating handle 52. Within the carbureting chamber 16 and surrounding the standpipe 20 is situated the baffle member 53 preferably formed from sheet metal and shaped to produce a flange 54 arranged to rest upon the bottom wall of the carbureting chamber between the standpipe and the side walls of said chamber, and from this flange 54 extends the upwardly and outwardly projecting wall 55 having perforations 56 therein, and from the upper portion of this wall extends the upwardly and inwardly projecting wall 57 having perforations 58 therein of smaller diameter than the perforations 56.

The upper and inner portion of the wall 57 terminates adjacent the standpipe 20, and from this portion of said wall extends the upwardly projecting imperforate guide wall 59, and from the upper portion of this wall extends the upwardly and outwardly projecting wall 60 having perforations 61 therein of less diameter than the perforations in either of the other walls. The other edge of this wall terminates adjacent the side walls of the carbureting chamber, and from this outer portion extends the upwardly projecting imperforate outer wall 62, and from the upper portion of this wall extends the inwardly projecting horizontal wall 63 having perforations 64 therein of still less diameter than the others, and this wall terminates adjacent the standpipe, from which portion extends the upwardly projecting imperforate guide wall 65, and from the upper portion of this guide wall extends the upwardly and outwardly projecting wall 66 on a less incline than the other inclined walls, and this wall 66 is provided with perforations 67 of less diameter than any of the others, and from the outer portion of this wall extends the upwardly projecting imperforate outer wall 68, from which extends the inwardly projecting horizontal wall 69 having perforations 70 therein of still smaller diameter than the perforations in any of the other walls, and from the inner portion of this wall extends the upwardly projecting imperforate flange 71 which surrounds the standpipe 20 and also acts as a guide wall.

The baffle member is placed in the carbureting chamber with the guide walls and upper flange preferably in contact with the standpipe and with the outer walls in contact with the walls of the carbureting chamber, so that the air and vapor as it passes through the carbureting chamber will be broken up and thoroughly mixed.

Beside the carbureting casing 7 and pref-

erably formed integral therewith is situated the gasoline reservoir 72, forming a float chamber 73, in communication with the carbureting chamber through the passageway 19. Into the inlet chamber 73 from the lower end thereof projects the vertical gasoline supply pipe 74 which communicates with the pipe leading from a gasoline supply tank, and said pipe 74 has a longitudinal passageway 75 therethrough, the upper end of which terminates in a valve seat 76 with which coacts a needle valve 77 slidably mounted in and guided by a threaded plug 78 mounted in a threaded opening 79 in the cap or cover 80 of the gasoline reservoir, said cover being preferably threaded into the reservoir.

The plug 78 is provided with downwardly projecting arms 81, in which are pivoted levers 82 connected with a collar 83 carried by the needle valve and with the arms 84 of the float 85. The plug 78 and the parts attached thereto are adjustable to regulate the predetermined height of the volatile liquid within the reservoir, and when the proper adjustment is obtained, the same is held in position by the cap 86 which acts as a jam nut, and is threaded upon the plug until it engages the outer surface of the cover 80.

From the interior of the reservoir or float chamber at its upper end leads a canal 87 with which alines the conduit 30, thereby forming a passageway from the interior of the reservoir 72 to the cup shaped member 27, so that when the engine to which the carburetor is connected is operating, the air in the reservoir will be sucked therefrom by the pulsations of the engine, thereby forming a partial vacuum within the reservoir, which will cause the volatile liquid contained in the supply tank to run into the reservoir regardless of the position of the supply tank with relation to the reservoir within certain limits, thereby making it unnecessary to place the supply tank at a greater height than the reservoir. The reservoir is also provided with a drip cock 88 in the bottom wall thereof, whereby said reservoir may be drained.

Within the standpipe 20 is formed a rib 89 having a passageway or gasoline duct 90 therein, the upper end of which is in communication with the interior of the standpipe, and this end of the opening is preferably on an angle and threaded as at 91 to receive the spray nozzle 92 which is threaded exteriorly. The lower end of the duct 90 is in communication through a channel 93 with the plunger chamber 94, the shell of which is formed integral with the carburetor casing 7, and the plunger chamber 94 is also in communication through two openings 95 and 96 with the carbureting chamber, and in the plunger chamber 94 is

slidably mounted the plunger 97 having a stem 98 passing through the gland 99 threaded in the open end of the plunger chamber 94, and to this stem 98 is secured a lever or means 100 for actuating the plunger in one direction, said plunger being normally forced toward the opening 93 by a spring 101 coiled about the stem of the plunger within the plunger chamber 94.

102 denotes a valve chamber formed in a shell interiorly with the carbureting casing, and with the shell of the plunger chamber, and this chamber 102 is separated from the chamber 94 by a partition 103 in which is formed a hole 104 thereby forming a communication between said chambers, and the chamber 102 is in communication with the carbureting chamber by an angular inlet opening 112.

Within the valve chamber 102 is mounted a valve 105 engaging a seat 106 formed in the valve chamber, and this valve is provided with an opening 107 passing entirely therethrough and arranged to align with the opening 112 and 104. The valve is held upon its seat by a spring 108 mounted within the valve chamber and coiled about the valve stem 109 carried by the valve and passing through the gland 110 threaded into the open end of the valve chamber. This construction makes it unnecessary to pack the valve chamber as the valve is always held upon its seat, and the openings which it controls are opened or closed by the rotation thereof which is accomplished by any suitable means such as a lever 111 mounted on the outer end of the valve stem.

When it is desired to start the engine to which my improved carburetor is attached, the same may be primed by merely drawing the plunger 97 outward against the action of its spring until the hole 96 is uncovered, or the plunger beyond the same, at which time the volatile fluid will enter the plunger chamber 94 between the plunger and the channel 93, the opening 95 acting as a relief so that any of the liquid in the plunger chamber back of the plunger will be forced out.

When the plunger 97 is released, its spring 101 will act thereon and quickly force it inward, thus forcing the liquid through the channel 93 and upward through the liquid duct 90, where it will be sprayed through the nozzle 92 into the standpipe 20. As the liquid is sprayed from the nozzle it will mix with the air drawn through the standpipe 20, either from the atmosphere through the openings 8, or from the shield 3, thereby forming the mixture which is drawn through the outlet pipe 36 into the engine cylinders.

After the engine has started the air will be drawn from the atmosphere through the openings 8 or from the shield 3, preferably

the latter as it is heated, and produces a richer mixture, and then through the inlet 6 and the screen 12 mounted thereon at which point foreign matter is eliminated, 5 then through the duct 13 into the annular passageway 14, where it is distributed evenly to all of the ducts or passageways 15, the air then passing through said ducts into the carbureting chamber through the 10 opening 17, the carbureting chamber containing the volatile liquid.

As the air passes through the volatile liquid, it will be mixed therewith and a very highly explosive mixture produced, which 15 will be drawn from the carbureting chamber through the openings 28 in the cup shaped member, into the outlet pipe 36 by the pulsations of the engine, and from which place the mixture is distributed to 20 the engine, the distribution being controlled by the throttle 51. If at any time a premature explosion should occur causing a back fire, the valve 39 will be automatically closed, and the pressure in the outlet pipe 25 36 relieved by the valve 46.

The carbureting chamber is supplied with the volatile liquid from the reservoir 72, through the passageway 19, so that the liquid in the carbureting chamber will be 30 maintained at the same height as that in the reservoir, which is maintained at a predetermined height by the float 85 which controls the needle valve 77, and this reservoir is supplied with volatile liquid from a supply 35 tank, and is caused to flow from said supply tank into the reservoir by the vacuum maintained in the upper portion of the reservoir through the medium of the canal 87 and conduit 30 which form a communication between the reservoir and a cup shaped member 27, the vacuum being produced by the pulsations of the engine which draws the air from the reservoir.

If for any reason it is not desirable to 45 pass the air through the volatile liquid as above described, the throttle valve 22 may be opened to permit the passage of air, through the standpipe, and the valve 105 opened to permit the passage of the volatile 50 liquid from the carbureting chamber 16 through the opening 112, through the opening 107 in the valve, the hole 104, the plunger chamber 94, the channel 93, the duct 90, and the nozzle 92 into the standpipe 55 20, where it will be mixed with the air to produce the mixture which is drawn into the outlet pipe 36 by the pulsations of the engine.

If found desirable the lever 111 and operating handle 23 may be connected together, so that as the valve 105 is opened, the throttle 22 will also be opened, thus permitting the two to be operated in unison when it is desired to use the two forms of 60 carbureting herein described.

Of course I do not wish to be limited to the exact details of construction as herein shown, as these may be varied within the limits of the appended claims without departing from the spirit of my invention.

70

Having thus fully described my invention, what I claim as new and useful, is—

1. A carbureter comprising a casing having an air inlet, an annular passageway at the upper end thereof, a vertical duct communicating with said passageway and the air inlet, a carbureting chamber having an outlet, small vertical air inlet ducts surrounding the carbureting chamber in communication with the annular passageway and the carbureting chamber at the lower end thereof, a cover for said casing provided with a depending cup shaped member said member having openings therein, means for regulating the size of said openings, a valve and throttle controlled outlet pipe carried by the cover and in communication with the cup shaped member, and a baffle member provided with a plurality of perforated walls situated in the carbureting chamber, the perforations diminishing in size successively from the lower to the upper end.

75

2. A carbureter comprising a casing having an air inlet, an annular passageway at the upper end thereof, a vertical duct communicating with said passageway and the air inlet, a carbureting chamber having an outlet, small vertical air inlet ducts surrounding the carbureting chamber in communication with the annular passageway and the carbureting chamber at the lower end thereof, a cover for said casing provided with a depending cup shaped member said member having openings therein, means for regulating the size of said openings, a valve and throttle controlled outlet pipe carried by the cover and in communication with the cup shaped member, and a baffle member provided with a plurality of perforated walls situated in the carbureting chamber, the perforations diminishing in size successively from the lower to the upper end.

80

3. A carbureter comprising a casing having an air inlet, an annular passageway at the upper end thereof, a vertical duct communicating with said passageway and the air inlet, a carbureting chamber having an outlet, small vertical air inlet ducts surrounding the carbureting chamber in communication with the annular passageway and the carbureting chamber at the lower end thereof, a cover for said casing provided with a depending cup shaped member said member having openings therein, means for regulating the size of said openings, a valve and throttle controlled outlet pipe carried by the cover and in communication with the cup shaped member, and a baffle member provided with a plurality of perforated walls situated in the carbureting chamber, the perforations diminishing in size successively from the lower to the upper end.

85

4. A carbureter comprising a casing having an air inlet, an annular passageway at the upper end thereof, a vertical duct communicating with said passageway and the air inlet, a carbureting chamber having an outlet, small vertical air inlet ducts surrounding the carbureting chamber in communication with the annular passageway and the carbureting chamber at the lower end thereof, a cover for said casing provided with a depending cup shaped member said member having openings therein, means for regulating the size of said openings, a valve and throttle controlled outlet pipe carried by the cover and in communication with the cup shaped member, and a baffle member provided with a plurality of perforated walls situated in the carbureting chamber, the perforations diminishing in size successively from the lower to the upper end, a standpipe within the carbureting chamber extending from top to bottom in communication with the air inlet and the cup shaped member, means communicating with the carbureting chamber and with said standpipe whereby a charge of gasoline may be sprayed into said standpipe, and a reservoir communicating with the carbureting chamber at the bottom thereof and with said cup shaped member at the top thereof.

90

5. A carbureter comprising a casing having an air inlet, an annular passageway at the upper end thereof, a vertical duct communicating with said passageway and the air inlet, a carbureting chamber having an outlet, small vertical air inlet ducts surrounding the carbureting chamber in communication with the annular passageway.

100

105

110

115

120

125

130

and with the carbureting chamber at the lower end thereof, a cover for said casing provided with a depending cup shaped member said member having openings therein, 5 means for regulating the size of said openings, a valve and throttle controlled outlet pipe carried by the cover and in communication with the cup shaped member, a baffle member provided with a plurality of perforated walls situated in the carbureting chamber, the perforations diminishing in size successively from the lower to the upper end, a standpipe within the carbureter chamber extending from top to bottom in communication with the air inlet and the cup shaped member, means communicating with the carbureting chamber and with said standpipe whereby a charge of gasolene may be sprayed into said standpipe, and comprising 10 a shell formed integral with the bottom of the carbureter casing at the lower end of the standpipe, said shell having a valve 15

20

chamber and a plunger chamber therein separated from each other, and in communication through a hole, the valve chamber being in communication with the carbureting chamber, a valve situated within said valve chamber, the plunger chamber having holes leading to the carbureting chamber, a plunger situated in said chamber, a rib in the standpipe having a longitudinal duct or passageway, a canal leading from the plunger chamber to the longitudinal duct, and a reservoir in communication with the carbureting chamber at the lower end thereof, the upper end of said reservoir being in communication with the cup shaped member. 25
